UNITED STATES PATENT OFFICE.

NATHANIEL M. ONG, OF YORK, PENNSYLVANIA.

SOUNDING-BOARD BRIDGE.

No. 824,040.

Specification of Letters Patent.

Patented June 19, 1906.

Application filed November 13, 1905. Serial No. 287,118.

To all whom it may concern:

Be it known that I, NATHANIEL M. ONG, a citizen of the United States, residing at York, in the county of York and State of Pennsylvania, have invented a new and useful Sound-
5 ing-Board Bridge, of which the following is a specification.

This invention relates to pianofortes, and more especially to the construction of the
10 bridges and the method of attaching the same to the sounding-board, the principal object of the invention being to provide a bridge which will permit full and free vibration of the entire sounding-board.

15 A further object of the invention is to provide a sounding-board bridge that is provided with attaching-feet arranged in staggered relation and connected to the surface of the sounding-board in any suitable manner,
20 so as to reduce the contact area of the bridge to the greatest extent, and, further, to so arrange said connecting-feet as to gradually increase the distance between the feet and increase the area of such feet from the bass to
25 the treble end of the bridge.

With these and other objects in view, as will more fully hereinafter appear, the invention consists in certain novel features of construction and arrangement of parts hereinafter fully described, illustrated in the accompanying drawings, and particularly pointed out in the appended claims.

In the accompanying drawings, Figure 1 is a face view of a sounding-board provided with
35 a bridge constructed in accordance with the invention. Fig. 2 is a sectional view of the same on the line 2 2 of Fig. 1. Fig. 3 is a detail perspective view of a portion of the treble bridge detached. Fig. 4 is a similar
40 view of the bass bridge detached.

Similar characters of reference are employed to indicate corresponding parts throughout the several figures of the drawings.

45 The sounding-board A is of the usual construction and is provided on its rear face with the usual diagonally-arranged ribs B.

On the front of the sounding-board is secured the bridge 10, forming the subject of
50 the present invention. This bridge is formed of wood or other suitable material arranged on the usual compound curve and is slightly wider at the bass than at the treble end. The bridge is provided with attaching-feet 12,

that are disposed in staggered relation—that 55 is to say, occur alternately on opposite sides of the bridge from one end to the other, so that the surface area in contact with the sounding-board will be reduced to a minimum and the board will be perfectly free to 60 vibrate. These attaching-feet are secured to the board by glue or otherwise and are arranged at points directly opposite the point of connection of the strengthening-ribs B. The distance between the feet gradually decreases 65 from the treble toward the bass end of the bridge, and the area of the feet at the bass end of the bridge is greater than the area at the treble end in order to form a support proportioned to the weight of the strings. 70

Below the treble bridge is arranged a bridge 10' for the overstrung wires, and in this case the attaching-feet are preferably arranged opposite each other, owing to the fact that the bridge is a comparatively short one. 75 The acoustic properties of this bridge are further developed by grooving or channeling the lower face of the bridge, as indicated at 15 in Fig. 4, the channel in this case being straight as distinguished from the relatively tortuous 80 channel that is formed by the staggered feet of the treble bridge; but in both cases there is a free channel between the bridge and the board, and the vibrations of the latter will not be interfered with to the same extent as 85 where the bridge is attached throughout its length to said board.

Having thus described the invention, what is claimed is—

1. In a pianoforte, a sounding-board, and 90 a bridge, the latter having a continuous longitudinal channel formed in its lower face and being further provided with spaced feet for attachment to the sound-board.

2. A sounding-board, and a bridge, said 95 bridge having staggered attaching-feet.

3. A sounding-board bridge having staggered attaching-feet arranged at gradually-decreasing distances from the treble to the bass end of the bridge. 100

In testimony that I claim the foregoing as my own I have hereto affixed my signature in the presence of two witnesses.

NATHANIEL M. ONG.
